FRICTION LOCK FOR SCREW THREADS

Ray Ensinger and James H. Foote, Detroit, Mich.,
assignors to George M. Holley and Earl Holley

Application April 8, 1944, Serial No. 530,210

2 Claims. (Cl. 151—7)

The object of this invention is to provide means for locking a threaded stud into a comparatively soft metallic casting.

It has heretofore been common practice to make a nut with a fiber inset spun into place, both nut and fiber being threaded on a bolt. When applying the same method to driving a stud into a casing, a different method of making the locking device has to be invented, because it is no longer possible to spin the casting over so as to engage the fiber insert.

In forcing the stud into the fiber insert, which is the preferred method, or in running an undersized tap into the fiber, the fiber must be held from rotating and also must be clamped tightly against end movement.

Hence, the object of this invention is to provide an inexpensive means for holding a fiber washer against rotation and also against end thrust.

Figure I shows the parts ready for assembly.

Figure II shows the locating ring.

Figure III shows the fiber washer.

Figure IV shows in cross-sectional elevation the fiber ring locked in place.

Figure V shows the plan view looking up on Figure II.

In the figures: 10 is the casting; 11 is fiber washer; 12 is a steel locking ring shaped in cross section like the letter L. The ring 12 has a corner 13 formed between the upper leg which makes an acute angle with the cylindrical extension 16, which forms the other leg of the L.

In Figure I the method of assembling is illustrated.

A punch 14 has a short extension 15, which engages with and forms a pilot for the inside of the cylindrical extension 16 of the steel ring 12. The drilled hole in the casting has a cylindrical portion 17, which is a little larger than the diameter of the outside diameter of the fiber washer 11. A portion 18 of the bore in the casting 10 has a larger diameter than the bore 17 so that a shoulder 19 is formed between the bores 17 and 18. The punch 14 when driven home presses the corner 13 of the steel ring 12 into the shoulder 19 between the two bores 17 and 18 in the casting. The outside diameter of the punch is a little less than the diameter of the bore 18. An axial load on the corner 13 of the washer 12 causes a lateral force to be exerted by the periphery of the washer which is thus forced into the casting, which may be aluminum or any other casting softer than the material of the steel ring. The serrations on the lateral and axial legs of the L of the ring 12 shown in Figure 5 prevent the fiber ring from rotating. Finally the fiber is tapped with an undersized tap so that the fiber will grip the bolt or stud tightly. The serrations on the outside diameter of the ring 12 which engage with the opening 18 just above the shoulder

19 prevent the ring 12 being pushed during the threading operation.

Operation

5 The fiber washer 11 is placed in the cylindrical portion 17. The steel washer 12 is placed above the fiber washer and is guided by the cylindrical bore. The punch 14 then descends and is guided into the bore 18. The pilot 15 on the end of the 10 punch enters the inside of the ring 12 and the shoulder of the punch engages with the corner 13 of the ring 12. The pilot 15 on the end of the punch 14 being slightly smaller than the inside diameter of the cylindrical portion 16 of the steel 15 ring 12, the punch 14 guides the ring into place. The steel ring 12 has a portion which is conical and when pressure is applied to the upper edge 13 it becomes flat and therefore spreads laterally. The inside diameter 16 cannot be reduced as it is 20 supported by the pilot 15. As a result, the outer edge of the flat disc thus formed is forced laterally into the casting at a plane just above the shoulder 19, into the metal matrix.

At the same time, the lower edge of the ring 12 25 is pushed into the fiber washer 11. The outer lateral edge of the steel ring 12 is serrated and the lower edge of the cylindrical portion 16 of ring 12 is also serrated. By these means, when these two metal edges of the ring 12 are forced, one down into the fiber, and the other, laterally into the casting, the fiber is thus locked in place and cannot rotate nor can it be pushed out. Subsequently a thread is formed on the fiber by 30 means of an undersized tap or the bolt itself 35 when forced up from the bottom of the opening will form a thread in the fiber.

The pilot 15 prevents the inner diameter 16 40 from interfering with the top of the thread and the locking ring being forced into the wall of the opening in the casting will not be pushed out. The serrations on the locking ring prevent the fiber disc rotating. Hence, a tight fiber thread is 45 formed as an extension to the thread in the casting 10.

45 What we claim is:

1. In a casting of relatively soft metal, a fiber bushing, and L shaped locking ring having an acute angle and serrated edges and made of relatively hard metal, the cylindrical portion of the 50 L being embedded in the fiber, the transverse portion of the L being forced into locking engagement with the relatively soft metal by the enlargement of the acute angle of the ring.

2. A fiber locking ring embedded in an opening 55 in a relatively soft metal matrix, a relatively hard metal ring having an L shaped cross section with serrated edges, the serrated edge of the axial portions engaging with the fiber washer, and the radial portion engaging with the metal matrix.
